(57) **CLAIM**

An ornamental design for an earring post, as shown and described.

DESCRIPTION

FIG. 1 shows an isometric view of an embodiment of an earring post;

FIG. 2 shows a frontal view thereof;

FIG. 3 shows a rear view thereof;

FIG. 4 shows a top view thereof;

FIG. 5 shows a bottom view thereof;

FIG. 6 shows a left view thereof; and

FIG. 7 shows a right view thereof.

FIG. 8 shows an isometric view of an embodiment of an earring post;

FIG. 9 shows a frontal view thereof;

FIG. 10 shows a rear view thereof;

FIG. 11 shows a top view thereof;

FIG. 12 shows a bottom view thereof;

FIG. 13 shows a left view thereof; and,

FIG. 14 shows a right view thereof.

The broken lines that illustrate an earring portion are for the purpose of illustrating environmental structure and form no part of the claimed design. The broken lines that illustrate portions of the earring post form no part of the claimed design.

1 Claim, 7 Drawing Sheets
